Patented Jan. 19, 1960

187,079

FOOD TURNER

Raymond O. Horn, Salem, Robert C. McClement, West Frankfort, and William F. Richmond, Herrin, Ill.

Application August 3, 1959, Serial No. 57,040

Term of patent 14 years

(Cl. D44—29)

Fig. 1 is a top plan view of a food turner showing our new design;

Fig. 2 is a rear view thereof;

Fig. 3 is a side elevational view thereof;

Fig. 4 is a front view thereof; and

Fig. 5 is a perspective view thereof.

We claim:

The ornamental design for a food turner, substantially as shown.
